DIVING MASK

Henry S. Wolfe, Jenkintown, Pa., assignor to
Sportsotron, Inc., Lynbrook, N.Y.

Filed Oct. 28, 1969, Ser. No. 19,775

Term of patent 14 years

Int. Cl. D2—03

U.S. Cl. D2—234

FIG. 1

FIG. 2

FIG. 3

FIG. 1 is a front perspective view of a diving mask in accordance with my new design.

FIG. 2 is a top plan view thereof.

FIG. 3 is a front elevational view thereof.

FIG. 4 is a rear elevational view thereof.

FIG. 5 is a bottom plan view thereof.

FIG. 6 is a side elevation thereof, the opposite side being a mirror image of the side shown.

I claim:

The ornamental design for a diving mask, as shown and described.
